A. S. BOYLE.
FLOOR WAXER AND POLISHER.
APPLICATION FILED MAR. 1, 1920.

1,406,721.

Patented Feb. 14, 1922.

Alfred S. Boyle ^{Inventor}

By Walter F. Murray ^{Attorney}

UNITED STATES PATENT OFFICE.

ALFRED S. BOYLE, OF CINCINNATI, OHIO.

FLOOR WAXER AND POLISHER.

1,406,721.

Specification of Letters Patent. Patented Feb. 14, 1922.

Application filed March 1, 1920. Serial No. 362,443.

To all whom it may concern:

Be it known that I, ALFRED S. BOYLE, a citizen of the United States of America, and a resident of Cincinnati, in the county of 5 Hamilton and State of Ohio, have invented a new and useful Improvement in Floor Waxers and Polishers, of which the following is a specification.

An object of my invention is a floor polishing device that will not require the operator to exert any appreciable downward pressure upon the handle, but will by its own weight supply sufficient frictional contact with the surface being polished so that the operator 15 need only supply the necessary force for propelling the device over the floor.

Another object of my invention is to provide simple means for mounting the waxing and polishing material on the base.

20 These and other objects are obtained in the polishing block described in the following specification and illustrated in the accompanying drawings, in which:—

Fig. 1, is a perspective view of a block embodying my invention.

Fig. 2, is an enlarged detail perspective view of a block embodying my invention.

Fig. 3, is a detailed longitudinal sectional view of a block and polishing material.

30 The waxing and polishing block embodying my invention comprises a weighted base adapted to support a waxing or polishing material, a spring adapted to clamp the opposite ends of the material, and adapted 35 to be moved over a surface by means of a rod or pole serving as a handle.

The block A is made preferably of heavy metal and has a depression a upon its back or upper surface a'. A rectangular arched 40 spring frame B fits in this depression. The spring is longer than the depression and is so tensioned that it can be arched sufficiently to permit its ends b and b' to be inserted between the ends a², a³ of the depression, and 45 when released therein, it will firmly seat the ends b and b' against the ends a² and a³ at their junction with the bottom of the depression. The polishing or waxing material C, which consists preferably of layers of 50 cloth, is applied on the face or under surface a' of the block and is held in position by having its ends c and c' extend upward over the ends of the block and then over the upper edge a. It is then turned down into the 55 depression and is bound at the junction of

ends a², a³ with the bottom of the depression by the ends b and b' of the spring. On the longitudinal sides of the block are formed lugs a⁵ and a⁶ having transverse apertures a⁷ adapted to accommodate a handle D. 60 Handle D has metal prongs d adapted to be sprung apart in order to attach the handle to the block. Lugs d' formed on the prongs are adapted to be seated in the apertures a⁷ in lugs a⁵ and a⁶.

61 The polishing material is fitted about the face of the block and extended over the transverse ends thereof and fastened by means of the arched spring. The waxing compound is inserted between two of the 70 layers of material and then the block is moved over the area to be waxed, by means of the handle affixed thereto. The weight of the block will be sufficient, together with the friction developed by the manipulation 75 of the block, to feed the wax through the material and to apply it to the area to be treated. The spring is lifted and the material containing the wax is replaced by clean material after this process and the 80 block is again manipulated over the waxed area, the treated area thereby being polished. Wax applied in this manner gives an even surface and a high polish and as a result of the evenness of the application, the finish 85 is found to be more endurable and therefore more economical.

86 The arched spring will have its center of tension at or near the center of the arch, so that when the spring is seated in the depression, all the force of the strain placed upon it will be directed toward the point of junction of the bottom and transverse ends of the depression, thereby holding the material 90 very securely.

95 What I claim is:—

In a floor wlexer and polisher, the combination of a heavy rectangular metallic block, having its face flat, and in its back a rectangular depression, and an arched rectangular wire frame, of a width substantially the width of the depression, and adapted to be sprung into, and to have its ends held, by the arch, against the end walls of, the depression.

In witness whereof, I have hereunto subscribed my name this 10 day of February, 1920.

ALFRED S. BOYLE.
